UNITED STATES PATENT OFFICE.

THEODORE MONROE CARPENTER AND FRED LINNEL BAKER, OF LOS ANGELES, CALIFORNIA.

VENTILATOR.

SPECIFICATION forming part of Letters Patent No. 703,762, dated July 1, 1902.

Application filed October 18, 1901. Serial No. 79,168. (No model.)

To all whom it may concern:

Be it known that we, THEODORE MONROE CARPENTER and FRED LINNEL BAKER, citizens of the United States, and residents of Los Angeles, in the county of Los Angeles and State of California, have invented a new and Improved Ventilator, of which the following is a full, clear, and exact description.

This invention relates to a ventilator for carrying off the impure gases from water-closets and various devices in sanitary plumbing. It is particularly adapted for use in connection with a flushing apparatus, and it comprises a motor driven by the water as it falls into the flush-tank, such motor operating an exhaust-fan for carrying off the gases from the vicinity.

This specification is a specific description of one form of the invention, while the claims 20 are definitions of the actual scope thereof.

Reference is to be had to the accompanying drawings, forming a part of this specification, in which similar characters of reference indicate corresponding parts in all the figures.

25 Figure 1 is a front view of the apparatus, showing it in use. Fig. 2 is a section on the line 2 2 of Fig. 3. Fig. 3 is a plan view showing the motor, the top of the exterior casing being removed; and Fig. 4 is a section on the line 4 4 of Fig. 2.

In Fig. 1, *a* indicates a flush-tank which is used in connection with the apparatus *b*. *a'* indicates a float which is arranged in the tank *a* and carried on an arm *a'*, connected 35 to a cock or valve *c'*, commanding the pipe *c*, through which the water-supply is led. When the water reaches the upper level in the tank *a*, it raises the float *a'*, and this throws the arm *a'*, so as to close the cock *c'* and cut off 40 the water in the supply-pipe *c*.

d indicates a casing which is supported on the flush-tank and also, if desired, by a chain from an overhead support. The casing *d* is preferably cylindrical in form and is provided 45 at its lower part with a funnel or hood *d'*, adapted to receive and carry into the casing the foul gases from the apparatus *b*. Within the lower part of the casing *d* works an exhaust-fan *e*. The casing is formed, as best 50 shown in Figs. 1, 3, and 4, with an outlet pipe or tube *d* for the gases drawn through the

hood *d'*. This outlet is provided with a gate *d*, which is normally closed, but is adjusted very delicately, so as to open in response to the slightest outward current within the outlet-conduit *d*. 55

Just above the fan *e* within the casing *d* is arranged a horizontal partition *f*, on which is mounted a stationary cone *f'*. This cone is fitted with a centrally-located tube *f*, provided with ball-cups working with ball-cones on a shaft *g*, passing centrally through the tube *f*. Antifriction-balls are interposed between the cups and cones, and thus the shaft *g* is mounted to turn freely. This shaft *g* carries a sleeve *e'*, adjustably held thereon by nuts *g'*, and to said sleeve *e'* is attached the fan *e*. Within the tube *f* is fitted a tube *f*, which forms, practically, a part of the tube *f*, and between these tubes *f* and *f* is arranged a tubular rubber gasket or packing *f* to hold the parts snugly together and reduce vibration. The tube *f* has at its upper end a conical hood *f*, which fits down snugly over the cone *f'* and has located between it and the cone *f'* an extension of the gasket *f*. At the lower circumference of the hood *f* is arranged an annular flange *f*, which is carried on the cone *f'* and extends upward therefrom to prevent the passage of water onto the hood *f*, and thus avoid the possibility of water entering 70 between the parts *f* and *f* and leaking down into the compartment in which the fan is located. 75

The upper end of the shaft *g* carries a motor 85 which comprises a disk *h*, located over the annular flange *f* and having a downwardly-projecting peripheral flange *h'*, carrying buckets *h*, against which a stream of water is continuously projected from the pipe *c* 90 while the apparatus is in operation. This stream of water turns the parts *h*, *h'*, and *h* and imparts a rotary movement to the shaft *g*, thus driving the fan.

h represents a water-outlet pipe passing 95 from the base of the cone *f'* to carry off the water used to run the motor. This pipe *h* empties into the flush-tank *a*. By the employment of the cone *f'* and arranging the pipe *h* at the base thereof, as shown, all the water 100 will be discharged from the casing through said pipe.

d^4 indicates a removable cover for the casing d , this cover lying directly over the motor.

In Fig. 3 the cover d^4 is supposed to have been removed.

- 5 In the operation of the device, assuming that the flush-tank is emptied by the ordinary device for that purpose, (not fully shown in the drawings,) the water will run out of the flush-tank and the float a' will fall, thus 10 opening the cock or valve c' of the pipe c . The water will then flow through the pipe c and operate the motor within the casing d . The water flowing into engagement with the buckets h^2 of the motor will drive the shaft 15 g , and this operates the fan e , thus driving off the foul gases through the outlet d^2 . The overflow from the motor passes by the pipe h^3 into the tank a , and as the water rises in the tank it lifts the float a' and when the 20 proper level of the float has been reached the cock c' is closed and the water is stopped from flowing through the pipe c .

It will be observed that this apparatus utilizes the force of the water flowing into the 25 flush-tank to operate it and that no extra force is required. There is no waste of water, since the water used by the motor passes into the flush-tank and is used again therein. While the invention is applicable to various 30 sanitary purposes, it is particularly applicable to the use here illustrated, for the reasons pointed out above.

Various changes in the form, proportions, and minor details of our invention may be 35 resorted to without departing from the spirit of our invention. Hence we consider ourselves entitled to all such variations as may lie within the scope of our claims.

Having thus described our invention, we 40 claim as new and desire to secure by Letters Patent—

1. In a ventilator of the character described, a casing having an upper and lower compartment, the lower compartment having an inlet 45 in its bottom and an outlet in its side, and the upper compartment having a conical bottom and provided with a water-supply pipe leading into the same above the bottom and a discharge-pipe leading from the bottom thereof, 50 a vertical shaft mounted in the casing and having its ends extending into the compartments, a water-wheel mounted upon the upper end of the shaft in the upper compartment and into which the apex of the conical bottom of the upper compartment extends, 55 said wheel being provided with peripheral buckets, and a fan mounted upon the lower end of the shaft in the lower compartment, as set forth.

60 2. The combination of a casing, a partition therein, a cone on the top of the partition, an outlet-pipe leading from the casing at the base of the cone, a tube passing from the apex of the cone down to the partition, a shaft 65 mounted in the tube, an annular flange arranged on top of the cone adjacent to its apex, a fan attached to the lower end of the shaft,

a disk attached to the upper end of the shaft above the said annular flange, and buckets carried by the disk at the periphery thereof, 70 the casing having inlet and outlet openings at each side of the partition, for the purpose specified.

3. The combination with a flushing-tank, 75 of a casing arranged adjacent to the flushing-tank and formed with an upper and lower chamber, the upper chamber having a conical bottom and the lower chamber having an inlet in its bottom and an outlet in its side, a horizontal water-wheel mounted in the upper 80 chamber and into which the apex of the conical bottom of the upper chamber extends, said wheel being provided with peripheral buckets, a fan in the lower chamber, the fan and wheel being mounted on a common shaft, 85 a supply-pipe leading into the upper chamber and discharging onto the buckets of the wheel, a valve in said pipe, a float in the flushing-tank and controlling the valve, and a pipe leading from the upper chamber into the 90 flushing-tank to convey the overflow of the wheel to said tank, as set forth.

4. The combination with a flushing-tank, 95 of a casing arranged adjacent to the flushing-tank and having two chambers one above the other, the upper chamber having a conical bottom, and the lower chamber having an inlet in its bottom and a valved outlet in its side, a hood projecting from the bottom of the lower chamber, a horizontal water-wheel mounted 100 in the upper chamber and into which the apex of the conical bottom of the chamber extends, said wheel having peripheral buckets, a fan mounted in the lower chamber, a vertical shaft mounted in the casing and carrying the 105 fan and wheel, a water-supply pipe leading into the upper chamber of the casing, and discharging onto the water-wheel, a valve in the said pipe, a float in the flushing-tank and controlling the valve and a pipe leading from the bottom of the upper chamber into the 110 flushing-tank to convey the overflow from the wheel to the said tank, as set forth.

5. The combination with a chamber having 115 a conical bottom, of a water-wheel mounted in the chamber and comprising a disk having a downwardly-projecting peripheral flange carrying buckets, and an annular flange arranged on the conical bottom of the chamber and extending upward to within a short distance of the body of the wheel, as and for the 120 purpose set forth.

6. The combination with a flushing-tank, 125 of a casing arranged adjacent to the flushing-tank and having two chambers one above the other, the upper chamber having a conical bottom and an outlet leading from the bottom into the flushing-tank, and the lower chamber having an inlet on its bottom and a lateral outlet, a fan in the lower chamber, a water-wheel in the upper chamber and comprising 130 a disk having a downwardly-projecting peripheral flange carrying buckets, the wheel and fan being mounted on a common vertical

shaft, an annular flange arranged on the conical bottom and projecting to within a short distance of the body of the wheel, a water-supply pipe leading into the upper chamber 5 of the casing and discharging onto the water-wheel, a valve in said pipe, and a float in the flushing-tank and controlling the valve, as set forth.

7. In a ventilator of the character described, the combination with a chamber provided with a conical bottom having a central opening, a tube fitting in the opening of the conical bottom and having a conical hood at its upper end fitting upon the conical bottom 15 of said chamber, a packing between the tube

and the wall of the opening of the bottom, a shaft projecting through the tube and a water-wheel mounted on the upper end of the shaft, said wheel comprising a disk having a downwardly-projecting peripheral flange carrying buckets, as set forth. 20

In testimony whereof we have signed our names to this specification in the presence of two subscribing witnesses.
